UNITED STATES PATENT OFFICE

CARROLL C. FIGGE, OF CHICAGO, ILLINOIS

ROOF AND SHINGLE THEREFOR

Application filed October 20, 1928. Serial No. 313,707.

This invention relates in general to a composition shingle of the individual type held down at the butt or projecting tip and to a roof composed of such shingles.

Among the objects of the invention are to provide an improved shingle with a thick butt constructed of composition roofing and having attached means for holding the shingle in place; to provide improved shingle holding means; to provide a shingle with a tip holding means which predetermines the location of each shingle with respect to those laid in advance of it; and in general to provide the shingle and roof as herein shown and described.

Other objects of the invention will appear hereinafter, the accompanying drawings illustrating a preferred embodiment of the invention.

In the drawings Fig. 1, represents a portion of a roof with shingles staggered in courses in accordance with the present invention; Fig. 2 is a perspective of the under side of a shingle with one form of shingle holding means; Fig. 3 is a perspective of the under side of a shingle having a wire attaching clip secured thereto; Fig. 4 is a perspective of a metal plate attaching clip; Fig. 5 is a perspective of a wire attaching clip for the shingle of this invention; and Fig. 6 is a fragmentary perspective of a modification.

One of the objections to shingles made of composition roofing is that even though they are coated with finely divided slate, granite or other minerals, the shingle does not have sufficient thickness at the butt to produce a shade line of noticeable depth when placed upon a roof, and the shingle does not have sufficient rigidity to hold it in place unless some kind of a holding device is provided. The present invention overcomes these objections by turning under two adjacent edges of a shingle, thus increasing the thickness of the exposed end of the shingle, giving the shingle increased rigidity along these edges, and sealing them against the moisture and the weather.

The adjacent turned under edges of the shingle form means for engagement of a butt

or tip fastening clip which may be secured thereto for the purpose not only of holding the turned under edges in place but also for providing means in positioning each individual shingle with the adjacent shingles of different courses in laying a roof.

Referring now more particularly to the drawings, a shingle 6 which may be of the ordinary well known composition roofing has two of its adjacent edges 7 and 8 turned under and cut at the ends so that they meet smoothly and do not overlap at the corner. The edges may be bent or formed under heat and pressure to avoid cracking or breaking the material of the shingle.

In order to hold the edges 7 and 8 in their folded positions and together at the corner, a thin strip 9 of metal or other suitable material is inserted under the edges 7 and 8 and sharpened tongues 10 struck up from the opposite edges of the strip 9 are inserted through the material of the shingle adjacent the corner thereof and the tips of these tongues are bent over upon the under side of the shingle to hold the folded edges 7 and 8 tightly in place and to hold the clip 9 attached to the shingle.

The outer or free end 11 of this clip is preferably rounded. The clip being of metal or other resilient material, it is easily raised from contact with the under side of the shingle so that it may be inserted beneath the edges of other shingles for holding the exposed tip of the shingle in place.

Instead of making the fastening device of a solid strip of metal, as shown in Figure 4, a wire holding clip 12 may be provided, as shown in Figure 5, rounded at one end 13 and having its ends 14 crossed and extending around the sides with the extremities 15 adapted to pierce the edges 7 and 8 of the shingle and clinch downwardly thereon, as shown in Figure 3. This will leave the rounded end 13 free to be inserted under other shingles for holding the tip or butt in place.

When this shingle is incorporated in a roof, the tip or point of the shingle may be placed downwardly, or in the case of a rectangular shingle, as shown, the shingles

may be overlapped in courses, as indicated in Figure 1. In laying the shingles in this fashion, it is necessary to build up the courses diagonally upon the roof, the shingles *a* being in one course, the shingles *b* in another course, and the shingles *c* in a third course.

- When arranged in this manner, the two corners of the shingle at the ends of the
10 turned under edges are secured in place by
nails 16 or other fastening devices and these
nails are located at such a distance apart
in adjacent shingles of one course that fast-
ening clips 9 (or 13) may be inserted there-
15 between and under the shingles which they
fasten in place. This serves the double pur-
pose of holding down the extremity of the
butt end and covers the adjacent nail heads
so that they do not present an unsightly
20 appearance or cause leaks in the roof. An-
other result obtained by this arrangement
is the positive and accurate positioning of
each succeeding shingle with respect to the
two adjacent shingles below it.
25 In the form shown in Fig. 6, a flat metal
clip 15 is attached to the under side of one
corner of a shingle 16 by prongs 17 stamped
out of the clip and clinched into and through
the shingle. The shingle may have its adja-
30 cent edges bent over as in Figs. 2 and 3,
or the corner may be bent under or cut off
on a line 18.

With these constructions the shingles are
complete in themselves when they arrive on
35 the job, it is not necessary to apply the
fastening devices after the shingles are in
place or partly in place, and the fastening
devices being flat will nest closely together
for packing and storage.

40 I claim:

1. The combination of a composition shin-
gle having adjacent edges turned under
forming an angular tip, a substantially flat
shingle positioning and tip holding device
45 having one end disposed between the turned
under edges and the under side of the shin-
gle and means engaging the said edges at
the corner for holding them together and
securing the device in place and the free
50 ends of the device extending toward the
central portion of the under side of the
shingle.

2. The combination of a composition shin-
gle having adjacent edges turned under
55 forming an angular tip, and a substantially
flat shingle positioning member secured be-
tween the said edges and the under side of
the shingle and holding the edges together,
and the free end of the member extending
60 toward the central portion of the shingle.

CARROLL C. FIGGE.
